George W. Rathbun, Le Roy, New York, Letters Patent No. 202. Patented Oct 24th 1848.

The Schedule referred to in these letters patent and making part of the same.

To all whom it may concern:

Be it known that I, George W. Rathbun of the town of Le Roy, in the County of Genesee, and State of New York, have invented a new Design for a Cook stove, which is described as follows, reference being had to the annexed drawings of the same making part of this specification.

Figure 1. is an elevation of one of the side plates of the cook stove

A.A. are the two front doors paneled on the outer surface and enriched with raised ornaments B.B. The central portion of the upper edge of the front plate, above the doors is projected forward in the form of a segment of a fustum of a cone and ornamented by flowers C, in bas-relief. The upper angles of the plate are also relieved by ornaments D.D.

The side door of the fire chamber and the oven door of this Cook Stove are made and arranged in the usual manner.
The space below the door of the fire chamber is paneled in raised work. The centre of this space is ornamented with the embellishment E. The panel of the door of the fire chamber is enriched by the figures F. The plain surface of the oven door is relieved by the ornamental work G. The spaces around three sides of the oven door are embellished by the ornaments H.
